UNITED STATES PATENT OFFICE.

HENRY F. LAMB, OF BELLINGHAM, WASHINGTON.

SEPARATOR.

1,159,962.

Specification of Letters Patent.

Patented Nov. 9, 1915.

Application filed February 14, 1913. Serial No. 748,455.

To all whom it may concern:

Be it known that I, HENRY F. LAMB, a citizen of the United States, residing at Bellingham, in the county of Whatcom and

5 State of Washington, have invented new and useful Improvements in Separators, of which the following is a specification.

10 My invention relates in general to separators and has particular reference to that 15 class of devices peculiarly adapted to separating sand from gravel or extracting the finer elements from the coarser ones in any similar substance.

The principal object of my invention 20 15 sides in the provision of means whereby the separated elements may be individually conveyed to vats, containers or similar structures.

25 The above and additional objects are accomplished by such means as are illustrated in their preferred embodiment in the accompanying drawings described in the following specification and then more particularly pointed out in the claim which is appended hereto and forms a part of this application.

With reference to the drawings throughout which similar reference numerals designate corresponding parts: Figure 1 is a 30 front elevation with portions of the box broken away to more clearly disclose the assembled relation of the various parts. Fig. 2 is an end elevation. Fig. 3 is a section on the line 3—3 of Fig. 1.

35 Proceeding now to the description of the drawings my invention includes the separator box designated as an entirety by the numeral 1, the conveyer chute 2, the outlet pipes 3 and 4, the worm 5, the screen 6 and 40 the agitating cams 7.

The box 1 is constructed according to the common practice and may be angularly supported by any suitable means. Hingedly mounted at the upper end of the box is the 45 worm housing 8, on the upper portion of which the conveyer chute 2 is seated. The housing 8 is provided with the hinged door 9 whereby access may be had to the worm 5 in the event that the mechanism becomes 50 clogged by the gravel. A door 10 is also carried by the housing 8 providing access to the interior of the box 1. Spaced from the lower end of the box and held in rigid relation thereto is the division wall 11 which 55 may be suitably braced by the members 12. The pipe 3 communicates with the chamber

formed by the spacing of the wall 11 from the lower end of the box and a pipe 4 is in communication with the upper chamber of the box.

60 The worm 5 is rotatably mounted within the housing 8 and is disposed to evenly distribute the incoming gravel along the upper portion of the screen 6. The baffle shelf 13 is secured to the wall of the housing by 65 the brace 14 and co-acts with the worm 5 in the distribution of the gravel. The screen 6 which is of the common type and is provided to permit the finer portions of the gravel to sift through into the upper compartment of the box, is secured at its lower end to the upper edge of the partition wall 11 and is pivotally connected at its upper end with the shaft 15 through the medium 70 of the connection 16. The screen 6 carries 75 on its under side the longitudinally extending series of plates 17, 18 and 19. Secured to the plates 17 and 19 are a plurality of helical springs, the lower ends of which are fixed to the rod supporting plates 20. The 80 plates 20 carry the stop rods 21 which are mounted within the spring and are adapted to engage the members 17 and 19 when the screen is forced toward the wall of the box 85 by the weight of the gravel.

85 In order to thoroughly separate the sand from the gravel, it is desirable that the screen be continuously agitated and to accomplish this result I employ the cams 7. These members are keyed to the rotatable 90 shaft 22 and are disposed for engagement in their rotation with the plates 18. The cam consists of a circular disk 23, having a plurality of strap members 24 secured thereto.

95 The above disclosures clearly explain the construction of my invention and I now pass to a brief explanation of the operation of the separator.

100 The gravel is introduced into the box through the chute 2 and falls upon the worm and shelf at the adjacent end thereof. The gravel is distributed by the worm evenly along the upper portion of the screen and then passes by the force of gravity along the inclined surface of the said screen. It 105 will be seen however, that if the shaft 22 is connected to the same means employed for rotating the worm, the screen will be given continuous agitations by the action of the strap 24 against the plates 19. The effect of 110 this agitation will of course be increased by the springs 20. As a result of the agitation

of the screen, the finer elements of the gravel will fall into the upper chamber of the box and will pass out through the pipe 4 while the coarser elements will continue along the 5 screen and drop into the lower compartment of the box subsequently passing out through the pipe 3 whence they may be conducted to any suitable container. In this connection it will be understood that while I have de- 10 scribed my invention as being peculiarly adaptable for the separation of sand and gravel, it may be also employed in separating the coarse and fine elements of any substance; and that while I have described the 15 pipes 3 and 4 as leading to containers, it will be seen that the box may be readily mounted in such manner as to permit the sand and gravel to fall directly into a wagon.

20 It will be further understood that various minor changes in details of construction and arrangement of parts may be made within the scope of the appended claim and without sacrificing any of the advantages of this 25 invention.

What is claimed is:

A separator comprising an inclined housing having an opening in the upper end

thereof, a vertical housing hingedly connected to the inclined housing and covering the opening therein, a conveyer leading into the top of the vertical housing, a conveyer screw rotatably mounted within the vertical housing below the conveyer, a rod extending transversely of the inclined housing near the upper end thereof, a screen pivotally connected to said transverse rod and terminating a distance from the opposite end of the inclined housing, springs supporting said screen, rods extending through said springs for limiting the movement of the screen, contact plates secured to the underside of the screen, a shaft extending transversely of the inclined housing near the lower end thereof, cams carried by said transverse shaft and adapted to engage the contact plates on the screen, a partition secured in the vertical housing adjacent the lower end of the screen, and outlet chutes leading from said inclined housing at each side of the 50 partition.

HENRY F. LAMB.
